ATTORNEY'S

UNITED STATES PATENT OFFICE.

CLARA FERGUSON, OF SAN FRANCISCO, CALIFORNIA, ASSIGNOR TO LEVI STRAUSS & COMPANY, OF SAN FRANCISCO, CALIFORNIA, A CORPORATION OF CALIFORNIA.

DESIGN FOR A WOMAN'S SUIT.

51,957.

Specification for Design.

Patented Apr. 9, 1918.

Application filed November 6, 1917. Serial No. 200,631. Term of patent 14 years.

To all whom it may concern:

Be it known that I, CLARA FERGUSON, a citizen of the United States, residing in the city and county of San Francisco and State of California, have invented a new, original, and ornamental Design for Women's Suits, of which the following is a specification, reference being had to the accompanying drawings, forming part thereof.

Fig. 2 is a rear view of the same.

I claim:

The ornamental design for a woman's suit, as shown.

CLARA FERGUSON.
